PAPER PULP SCREENING MACHINE

Nelson M. Knight, Brookline, Mass.

Application September 17, 1932, Serial No. 633,596

11 Claims. (Cl. 92—34)

This invention relates to a machine for screening paper pulp and particularly to that type of paper pulp-screening machine which comprises a vat or container having an inlet and an outlet, a cylindrical screen situated within the vat between the inlet and outlet, a plunger or pulsator within the screen, and means to vibrate the same in the direction of the axis of the screen, such operation keeping the pulp agitated and also assisting to keep the screen clear.

One object of my present invention is to provide an improved pulp-screening machine of this type which has novel means for keeping the screen plate clean.

Another object of the invention is to provide a pulp-screening machine which will have an increased pulp screening capacity and at the same time a relatively low power consumption for operation.

Another object of the invention is to provide a pulp-screening machine which has relatively few moving parts and which is constructed to ensure long life.

Other objects of the invention are to improve generally pulp-screening machines in the particulars hereinafter set forth.

In the drawings wherein I have illustrated a selected embodiment of my invention, Fig. 1 is a vertical sectional view through a pulp-screening machine embodying the invention taken on the line 1—1, Fig. 3;

Fig. 2 is an end view of the pulp-screening machine looking from the right Fig. 1;

Fig. 3 is a section on substantially the irregular section line 3—3, Fig. 1.

The machine herein shown comprises a casing or housing indicated generally at 1 and which is provided in its bottom with an inlet port 2 through which the pulp to be screened is delivered to the vat, and with an outlet port 3 at each end through which the screened pulp is discharged from the vat or casing 1. Each inlet port 3 communicates with a delivery conduit 4 through which the screened pulp is delivered.

Situated within the vat or casing 1 and between the inlet 2 and discharge ports 3 is a cylindrical screen member 5 so that in passing from the inlet to the discharge ports the pulp is compelled to pass through the screen member, this being a common construction in pulp-screening machines of this type.

While the vat or casing 1 may have any suitable construction that herein shown comprises a base member 6 in which the inlet opening 2

is formed, circular end frames 7 secured to the base 6, and end walls or end members 8 which form the ends of the vat or casing and are suitably secured to the end frames 7. The discharge ports 3 are formed in these end members 8 and the discharge conduits 4 are secured to said end members. The end members 8 are formed with conical-shape inner faces as indicated at 9, the apices of the conical faces 9 being directed toward each other.

The enclosing side walls 10 of the vat or casing 1 are in the form of side plates 50 which are secured at their lower edges to the base member 6 and at their upper edges to a top frame member 11 which extends from one end frame 7 to the other and is secured to both end frames. This top frame member 11 is provided with an opening 12 through which the dirt screened from the pulp may be ejected. The side plates 50 are also secured at their ends to the end frames 7.

The cylindrical screen member 5 is stationarily supported on the end members 8. For this purpose said end members are formed with annular seats 13 which are encircled by the ends of the screen 5, the latter being clamped to said seats by means of two-part clamping rings 14 which encircle the ends of said screen and the meeting ends of which are clamped together as indicated at 15.

Situated within the stationary cylindrical screen is a plunger or pulsating member indicated generally at 16 and which is shown as mounted upon a shaft 17 that slides back and forth in bearings 18 formed in the end members 8. The plunger 16 is in the shape of a double cone, that is, the opposite faces 19 thereof are cone-shaped with the apices of the cones directed in opposite directions. This pulsating member 16 has a diametrical dimension sufficient to nearly fill the cylindrical screen 5. Means are provided for vibrating the shaft 17 and the plunger 16 in an axial direction. Such pulsating movement operates to force the pulp back and forth through the screen thereby to keep the latter from clogging up.

While any suitable means may be employed for thus pulsating or vibrating the plunger 16 I have herein illustrated for this purpose a drive shaft 20 which is journaled in a crank case housing 21. Said housing is shown as secured to a draining drum 22 which in turn is secured to one of the heads 8.

The shaft 20 which may be driven by a pulley 23 or by any suitable means, is provided with an eccentric 24 which is encircled by an eccentric

strap 25 carried on the end of a link or connecting rod 26. This connecting rod is pivoted at 27 to one end of the shaft 17 which projects through the draining drum 22 and into the crank 5 case housing 23. Said housing may be supplied with oil as indicated at 28 to provide lubrication. With this construction the rotation of the shaft 20 will cause the plunger 16 to pulsate or vibrate from one dotted line position Fig. 1 to 10 the other.

When the device is in use the top frame member 11 is connected to a discharge conduit through which the dirt, foreign matter and other material to be ejected, is discharged and the 15 pulp will be delivered to the inlet 2, which it will be noted is situated centrally at the bottom of the vat or casing under a sufficient head to maintain the tank filled at least up to and preferably slightly into the opening in the frame 20 member 11.

When the plunger 16 moves to the right Fig. 1 the chamber 39 between the right hand face 19 of the plunger 16 and the right hand head member 8 will be reduced in size with the result 25 that a portion of the paper pulp or fibre-water mixture which is within the screen 5 and which, therefore, has been screened, is forced through the right hand discharge port 3 into the discharge conduit 4 while another portion of said 30 screened pulp will be forced outwardly through the screen 5. During this same stroke of the plunger 16 by which the chamber 39 is decreased in size the chamber 40 on the opposite side of the plunger will be increased in size and the 35 increase will produce a reduction in pressure within the chamber 40. The forcing of the pulp outwardly through the screen from the chamber 39 as above described tends to create an increased pressure of the pulp on the outside of the screen. 40 This increased pressure outside the screen together with the reduced pressure in the chamber 40 will cause the fibre-water mixture to pass 45 inwardly through the screen into the chamber 40. Hence when the plunger 16 moves to the right there will be a flow of fibre-water mixture outwardly through the screen from the chamber 31 and to the right between the screen and the casing and inwardly through the screen into the chamber 40.

When the plunger 16 is moved in the opposite direction or to the left in Fig. 1 the chamber 40 will be decreased in size and the chamber 39 will be increased in size. The reduction in size of the chamber 40 will cause part of the fibre-water mixture therein to be forced outwardly through the left hand discharge port 3 and will also cause part of said fibre-water mixture to be forced outwardly through the screen into the space between the screen and the walls 55 of the casing, thereby tending to increase the pressure of the fibre-water mixture outside of the screen. The increase in size of the chamber 31 tends to reduce the pressure of said chamber and this together with the pressure of the fibre-water mixture outside of the chamber causes a 60 movement of the fibre-water mixture from the chamber 40 around the plunger 16 and into the chamber 39.

This pulsating of the fibre-water mixture through the screen serves to prevent the screen from becoming clogged and during this operation the dirt or foreign matter which is screened 70 from the pulp or fibre-water mixture will remain on the outside of the screen and will be discharged through the opening 12 of the top frame 75

11 into a suitable receptacle as usual in pulp-screening machines of this general type.

To assist in keeping the screen clean I have provided a plurality of cleaner rings 29 which are situated within the cylindrical screen 5 and are of a size so that their peripheries are closely adjacent the inner face of said screen. These cleaner rings are connected to the plunger 16 and thus have pulsating or vibrating movements therewith. These cleaner rings are shown as 10 annular rings which are mounted on rods 30 that are supported in the peripheral portion of the plunger 16. The adjacent rings are separated by suitable spacers 31 carried by the rods. The peripheries of the cleaner rings 29 are preferably 15 bevelled as shown at 32 and the bevel faces 32 of the cleaner rings on the right hand side of the plunger are bevelled in an opposite direction from those on the left hand side of said plunger. The vibrating movement of these 20 cleaner rings assists the action of the plunger in keeping the screen from clogging up during the screening operation.

The head members 8 are provided with suitable water seals 33 to prevent leakage of water 25 along the shaft. The draining drum 22 has an opening 34 in its bottom and it provides means whereby any water which may leak past the water seal 33 in the right hand head member 8 may be drained away, and will thus be prevented from being carried into the crank casing 21.

I claim:

1. A pulp-screening machine comprising a casing having an inlet and an outlet, a cylindrical screen within said casing situated between the inlet and the outlet, a plunger element within the cylindrical screen, means to vibrate said element in an axial direction, and screen-cleaning means separate from the plunger but secured thereto and 40 vibrating therewith.

2. A pulp-screening machine comprising a casing having an inlet and an outlet, a cylindrical screen within said casing situated between the inlet and the outlet, a plunger element within the cylindrical screen, means to vibrate said element in an axial direction, and a series of screen-cleaning rings extending from one end of the screen to the other, means for securing said rings to the plunger to vibrate therewith, said rings 50 having their peripheries closely adjacent the inner face of the screen.

3. A pulp-screening machine comprising a casing having an inlet and an outlet, a cylindrical screen within said casing situated between the inlet and the outlet, a plunger element within the cylindrical screen, means to vibrate said element in an axial direction, rods carried by said plunger and extending parallel to the axis of the cylinder and cleaner rings mounted in spaced relation 60 on said rods, the peripheries of the cleaner rings being situated closely adjacent the inner face of the screen.

4. A pulp-screening machine comprising a casing having an inlet and an outlet, a cylindrical screen within said casing situated between the inlet and the outlet, a plunger element within the cylindrical screen, means to vibrate said element in an axial direction, rods carried by said plunger and projecting from each face thereof, and cleaner rings carried by the rods on each side of the plunger.

5. A pulp-screening machine comprising a casing having a central inlet and an outlet at each end, each end wall of the casing being cone- 75

shaped, a cylindrical screen within the casing situated between the inlet and the outlet, a shaft mounted in bearings in said end walls, a plunger carried by said shaft and having cone-shaped ends, means to reciprocate the shaft in the direction of its length, and cleaner rings secured to and reciprocating with said plunger, the peripheries of the cleaning rings being situated closely adjacent the inner face of the screen.

5 6. A pulp-screening machine comprising a casing having a central inlet in its bottom and a discharge port in each end, a cylindrical screen stationarily mounted within the casing and situated between the inlet and the discharge ports, a plunger element within the cylindrical screen, and means to vibrate said plunger element in an axial direction.

10 7. A pulp-screening machine comprising a casing having an inlet and an outlet, a stationary cylindrical screen within the casing situated between the inlet and the outlet, a plunger element within the cylindrical screen, means to vibrate said element in an axial direction, and a series of screen cleaning rings extending from one end 15 of the screen to the other and carried by and moving with said plunger.

20 8. A pulp-screening machine comprising a casing having a cylindrical side wall and two end members to which the side wall is secured, said side wall having a central inlet in the bottom of 25 the casing and each end member having a discharge port therethrough, a stationary cylindrical screen situated between the inlet and the discharge ports and having its ends supported by and 30 stationarily mounted on the end members, a plunger element within the cylindrical screen, and means to vibrate said plunger element in an axial direction.

9. A pulp-screening machine comprising a casing having a cylindrical side wall and two end members to which the side wall is secured, said side wall having a central inlet in the bottom of the casing and each end member having a discharge port therethrough, a cylindrical screen situated between the inlet and the discharge ports and having its ends supported by and mounted on the end members, a plunger element within the cylindrical screen, means to vibrate said plunger element in an axial direction, and means separate from the plunger but mounted thereon and vibrating therewith for cleaning the screen throughout its entire length.

10 15 10. A pulp-screening machine comprising a casing having a side wall and two end members, said side wall having an inlet in the bottom of the casing and each end member having a discharge port therethrough, a stationary screen situated between the inlet and the discharge ports, said screen having a tubular shape and having its ends secured to and supported by the end members, and means within the screen to cause the pulp to flow back and forth through the screen during its movement from the inlet to the discharge ports.

20 25 11. A pulp-screening machine comprising a casing having a side wall and two end members, said side wall having an inlet in the bottom of the casing and each end member having a discharge port therethrough, a stationary screen situated between the inlet and the discharge ports, said screen having a tubular shape and having its ends secured to and supported by the end members, a plunger element within the screen, and 30 means to vibrate said plunger element in the direction of the axis of the screen.

35 NELSON M. KNIGHT.
